US0D1033426S

(12) **United States Design Patent** (10) Patent No.: **US D1,033,426 S**
(45) Date of Patent: ** *Jul. 2, 2024

(54) **ELECTRONIC DEVICE**

(71) Applicant: **Samsung Electronics Co., Ltd.**, Suwon-si (KR)

(72) Inventors: **Junyong Song**, Suwon-si (KR); **Byoungjin Kim**, Suwon-si (KR); **Woohyeok Jeong**, Suwon-si (KR); **Eunsoo Kim**, Suwon-si (KR); **Junghyun Choi**, Suwon-si (KR)

(73) Assignee: **SAMSUNG ELECTRONICS CO., LTD.**, Suwon-si (KR)

(*) Notice: This patent is subject to a terminal disclaimer.

(**) Term: **15 Years**

(21) Appl. No.: **29/882,234**

(22) Filed: **Jan. 12, 2023**

Related U.S. Application Data

(63) Continuation of application No. 29/748,579, filed on Aug. 31, 2020, now Pat. No. Des. 978,140.

CLAIM

The ornamental design for an electronic device, as shown and described.

DESCRIPTION

FIG. 1 is a front perspective view of an electronic device showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines in the figures illustrate portions of the electronic device that form no part of the claimed design.

1 Claim, 7 Drawing Sheets
